US0D1026311S

(12) **United States Design Patent** (10) **Patent No.:** **US D1,026,311 S**
(45) **Date of Patent:** ** **May 7, 2024**

(54) **HAIR DRYER**

(71) Applicant: **Dyson Technology Limited**, Wiltshire (GB)

(72) Inventors: **Wei Phang Lim**, Singapore (SG); **Callum Wright**, Bristol (GB); **Nathan Andrew Thomas**, Bath (GB); **James Robert Alexander Fisher**, Swindon (GB); **Gerald Eng**, Singapore (SG); **Graeme McPherson**, Singapore (SG); **Simon Brian McNamee**, Bristol (GB); **Edward Sebert Maurice Shelton**, Swindon (GB); **Stephen Benjamin Courtney**, Gloucester (GB); **Peter David Gammack**, Gloucester (GB); **Leanne Joyce Garner**, Bristol (GB); **Laura Anne Howard**, Gloucester (GB)

(73) Assignee: **Dyson Technology Limited**, Wiltshire (GB)

(**) Term: **15 Years**

(21) Appl. No.: **29/806,226**

(22) Filed: **Sep. 1, 2021**

(30) **Foreign Application Priority Data**

Mar. 2, 2021 (EM) 008448831-0004

(51) **LOC (14) Cl.** **28-03**

(52) **U.S. Cl.**

USPC **D28/13**

(57) **CLAIM**

The ornamental design for a hair dryer, as shown and described.

DESCRIPTION

FIG. 1 is a perspective view of a hair dryer, illustrating our new design;

FIG. 2 is a front view thereof;

FIG. 3 is a rear view thereof;

FIG. 4 is a left side view thereof;

FIG. 5 is a right side view thereof;

(Continued)

FIG. 6 is a top view thereof; and,
FIG. 7 is a bottom view thereof.

The broken lines depict portions of the hair dryer that form no part of the claimed design.

1 Claim, 7 Drawing Sheets
